UNITED STATES PATENT OFFICE

118,363

DESIGN FOR A VASE OR SIMILAR ARTICLE

Frank L. Betz, Los Angeles, Calif.

Application September 2, 1939, Serial No. 87,033

Term of patent 7 years

To all whom it may concern:

Be it known that I, Frank L. Betz, a citizen of the United States, residing at Los Angeles, in the county of Los Angeles, State of California, have invented a new, original, and ornamental Design for a Vase or Similar Article, of which the following is a specification, reference being had to the accompanying drawing, forming a part thereof.

The sides opposite to those shown in Figures 1 and 2 are the same in appearance as the respective sides shown.

I claim:

The ornamental design for a vase or similar article, as shown and described.

FRANK L. BETZ.
